SUCTION CLEANER ATTACHMENT FOR CLEANING VENETIAN BLINDS OR THE LIKE

George H. Berleme, 69 Speight Road,
Auckland, New Zealand

Filed Aug. 18, 1961, Ser. No. 66,416

Term of patent 3½ years

(Cl. D9—2)

FIG. 1

FIG. 3

FIG. 1 is a side elevational view of a suction cleaner attachment for cleaning venetian blinds or the like showing my new design;

FIG. 2 is a front elevational view thereof; and
FIG. 3 is a rear elevational view thereof.

The side not shown has substantially the same configuration as has the side shown in FIG. 1, except for the fact that it is the mirror image thereof.

I claim:

The ornamental design for a suction cleaner attachment for cleaning venetian blinds or the like, as shown and described.
